UNITED STATES PATENT OFFICE.

JOSEPH A. WOLLÉ, OF PHILADELPHIA, PENNSYLVANIA, ASSIGNOR TO HALE-KILBURN METAL COMPANY, OF PHILADELPHIA, PENNSYLVANIA, A CORPORATION OF PENNSYLVANIA.

CAR-SEAT.

No. 844,224.

Specification of Letters Patent.

Patented Feb. 12, 1907.

Application filed September 14, 1905. Serial No. 278,431.

To all whom it may concern.

Be it known that I, JOSEPH A. WOLLÉ, a citizen of the United States, and a resident of Philadelphia, in the county of Philadelphia and State of Pennsylvania, have invented certain new and useful Improvements in Car-Seats, of which the following is a specification.

The present invention relates to the same class of apparatus as that disclosed in Letters Patent 778,219, granted December 27, 1904; and its object is to provide a structure of this character which shall possess maximum strength and the several parts whereof shall be capable of ready and easy assemblage.

A further object is to desirably simplify the construction of such apparatus and to provide means of a simple but effective nature for securing the structure in a railway-car or other vehicle.

In carrying out the invention practically the entire construction save the seat and back cushions (which may be upholstered) is constructed of pressed or cast steel or other suitable metal, whereby I attain not only lightness combined with adequate strength, but am also enabled to reduce the number of parts employed and to provide a structure which is graceful as well as useful.

The invention is illustrated in the accompanying drawings, in which—

Figure 1 is a side elevation of a car-seat employing my invention, certain parts being shown in section. Fig. 2 is a central horizontal section on the line 2 2, Fig. 1, the seat and back cushions being removed. Fig. 3 is a vertical section on the line 3 3, Fig. 1. Fig. 4 is a plan view of one of the supporting-legs and its contained structure detached from the seat-frame. Fig. 5 is an enlarged sectional view illustrating the construction of the front ledges or rails of the seat, and Figs. 6 and 7 are enlarged sectional views illustrating the construction of the arm-rest shown in Fig. 1.

Referring to these drawings, in which similar letters denote corresponding parts, I premise with the statement that both sides of the seat (one side being shown in Fig. 1) may be the same in construction, or, if desired, there may be but one such side member, (the aisle end of the seat,) the other end

of the mechanism being supported upon the car-wall. In either event a description of one side will suffice. Primarily the seat-frame comprises a cushion and back supporting structure, and this in turn is mounted upon suitable legs, which in the present instance are secured to the car-floor.

The side frame of the seat-body comprises two outer side plates A A', here shown as of a generally triangular shape and provided at their adjacent edges with inturned flanges a a'. Adjacent to the lower edges of the plates A A' the same are bowed or beaded, as shown at a², the extreme edges being flanged inwardly, as shown at a³.

Lying parallel with the two outer side plates A A' are two inner side plates B B', the adjacent edges of which are flanged inwardly at b b' on either side of the flanges a a' of the outer side plates, all four thicknesses of metal being here shown as united by means of rivets b², there being a similar rivet b³ passing through the flanges a a' only. The inner side plates B B' are provided with inclined shoulders b⁴, forming supports against which abut the back-cushion frames C C. Said inner side plates B B' are also provided with ledges b⁵, forming supports for the seat-cushions D D. At their lower edges the inner side plates B B' are flanged inwardly, as shown at b⁶, in contact with correspondingly-extended flanges a³ of the outer side plates A A'. These meeting flanges may be secured together in any suitable manner—as, for instance, by soldering or by riveting.

The upper curved edges of the inner and outer side plates A A' and B B' are provided with oppositely-turned beads E E', and over these beaded edges extends an arm-rest cap E², the sides e whereof are of a shape corresponding to that of the beads E E'. This cap may, if desired, be made of brass or of other metal either the same as or contrasting with the metal of which the side plates A A' and B B' are formed.

E³ designates a strengthening-rib, here shown as angular in cross-section, the purpose of which is not only to strengthen the arm-rest portion of the frame, as just described, but also to expand the inner and outer side plates against the inturned face of the arm-rest cap E², thereby firmly securing

these parts in position. This is accomplished by placing the inner and outer side plates adjacent to each other and then placing the arm-rest cap E² in a position as shown in Fig. 5. The strengthening-rib E³ may then be introduced at the upper portion of the seat-frame and forced between the beads E E' throughout their full extent, thereby firmly locking the several parts together, as illustrated in Fig. 6. The upper extremities of the inner and outer side plates and of the beaded edges thereof may then be covered by the corner-piece F, which may be of ornamental design and which may be secured to the side plates in any suitable manner.

The front rails or ledges G of the seat are preferably formed each of two thicknesses of metal comprising the outer member g, the upper edge whereof is provided 20 with a flange g' and the lower edge with a flange g² and the flange g³ in a plane parallel with the flange g². The inner member g⁴ is provided with a flange g⁵, adapted to be received between the flanges g' and g² and secured in such position either by solder or rivets. The upper portion of the inner member g⁴ is provided with the ledge or shoulder g⁶ and the flange g⁷, which may in like manner be secured to the flange g' of the outer 30 member of the ledge or rail. If desired, corner-pieces H may be employed, completing the union between the ledges or rails G and the outwardly beaded or bowed portion a² of the outer side plates A A'. As shown in Fig. 35, the shoulder g⁶ of the rail G receives and supports the outer edge of one of the seat-cushions D, the inner edge of said cushion being supported by means of the shoulders b⁵ of the inner frame members B B'. The inner 40 and outer side members A A' and B B', constituting one side frame of the structure, may be connected with corresponding members forming the side frame at the other side of the seat in any suitable manner—as, for instance, by the connecting-pieces H' H'.

Intermediate of its ends the structure may be provided with a support I, and, if desired, this may be provided with means for securing the lower end thereof to the floor. Such 50 means, however, may be omitted when the supporting-legs, now to be described, are employed and secured to such floor.

I designates a metallic foot, shown in Fig. 4 as of spider shape and provided with perforations l, adapted to receive the screws, by means whereof said foot may be secured to the floor. Said foot is centrally provided with a threaded socket adapted to receive and engage with the correspondingly-threaded end of the rod l', passing through the leg l². l³ designates a brace extending between and secured to the flanges a³ and b⁶ of the side frames and the flanges g², g³, and g⁶ of the front rails or ledges. The upper edge l⁴ of the leg l² abuts against the under side of this

brace. Said brace is provided with an upwardly-bowed portion l⁵, through which extends a perforation adapted to receive the rod l', the upper end whereof is threaded, as shown in Fig. 1. l⁶ designates a block the under surface whereof is hollowed out on a curvature corresponding to that of the bowed portion l⁵. Said block is also provided with a perforation permitting the rod l' to pass therethrough. l⁷ designates a nut adapted to coact with the screw-threaded upper end of the rod l' above said block l⁶.

In securing the seat-frame in a car the foot L is first located and by the screws above referred to firmly secured to the floor. The rod l' is then screwed into the threaded orifice of said foot, after which the leg l² is placed in position, thereby concealing the foot L and rod l' from view. When the frame is applied, the rod l' is passed through the opening in the brace l³ and through the orifice in the block l⁶, whereupon the nut l⁷ may be screwed upon the upper threaded end of said rod, and the frame thus firmly anchored to the floor.

As will be seen, the construction as above described is extremely simple and involves relatively few parts. Moreover, such parts are capable of ready and easy assemblage and when so assembled are brought into a definite and permanent mechanical relation, not to be disturbed either by hard use or by the jolting and jarring of the car in which the seat is installed.

It is evident that the construction may be varied in certain respects without departing from the invention herein disclosed or certain features thereof. Thus, so far as concerns the arm-rest and parts adjacent thereto and so far as concerns the supporting-feet and legs, it is not essential that the seat be of the double-facing type illustrated in Fig. 1. These among other features of the invention, as will be readily understood, may be employed in a seat structure designed to be placed along the side wall of the car and to face, therefore, in but a single direction.

What I claim, and desire to secure by Letters Patent, is—

1. In a car-seat, the combination with back and seat cushions, of a side frame comprising inner and outer members, each of said members being formed in two parts, having inturned flanges, said flanges being secured together, substantially as described.

2. In a car-seat, the combination with back and seat cushions, of a side frame, comprising inner and outer sheet-metal plates secured together and an arm-rest at the upper edge thereof, said inner plate having a shoulder formed thereon coacting with the seat-cushion, substantially as described.

3. In a car-seat, the combination with back and seat cushions, of a side frame, comprising inner and outer members secured to

- gether, said inner member having a shoulder coacting with the back-cushion, substantially as described. 45
4. In a car-seat, the combination with 5 back and seat cushions, of a side frame, comprising inner and outer members secured together, said inner member being provided with shoulders coacting with said back and seat cushions, substantially as described. 50
- 10 5. In a car-seat, the combination with back and seat cushions, of a side frame comprising inner and outer members, each of said members being formed in two parts, said parts having abutting inturned flanges 55 secured together, substantially as described. 55
- 15 6. In a car-seat, the combination with back and seat cushions, of a side frame comprising inner and outer members, the lower edges thereof being flanged inwardly and secured together, substantially as described. 60
- 20 7. In a car-seat, the combination with 65 cushions and means for supporting the same, of a side frame comprising two generally parallel members, the upper edges whereof are oppositely beaded and provided with an arm-rest cap and a strengthening-rib, substantially as described. 70
- 25 8. In a car-seat, the combination with a 75 cushion, of a side frame comprising two generally parallel members, an arm-rest cap extending over the adjacent edges of said members, and a strengthening-rib lying within said cap, said cap being held in position, relatively to said members, under pressure, substantially as described. 80
- 30 9. In a car-seat, the combination with a cushion, of a side frame comprising two generally parallel members, the upper edges whereof are oppositely beaded, an arm-rest 85 cap, the edges whereof are curved correspondingly with said beaded edges, and which extends over and covers the said beaded edges of said members, and a strengthening-rib within said cap, substantially as described. 90
10. In a car-seat, the combination with a cushion, of a side frame and a coacting end frame or ledge, said ledge being formed in two parts, each part being provided with flanges, those of one part being secured to 95 those of the other, substantially as described. 100
11. In a car-seat, the combination with a frame and cushions, of a foot adapted to be secured to the floor, a brace extending across a corner of said frame, a rod coacting at one 105 end with said foot and at the other with said brace, and a leg inclosing said rod and supporting said frame, substantially as described. 110
12. In a car-seat, the combination with a frame and cushions, of a foot adapted to be secured to the floor, a rod extending upward from said foot, a leg inclosing said rod and foot, its upper end coacting with said frame, 115 said frame having an upwardly-bowed portion adjacent to the point of coaction with said leg, a block overlying said portion, said rod extending through said portion and said block, and a nut coacting with the upper extremity of the said rod, substantially as 120 described. 125
13. In a car-seat, the combination with a seat-cushion, of means for supporting the same, including a front rail formed in two joined sections having a substantially horizontal portion coacting with the under side of the cushion and a substantially perpendicular portion coacting with the forward edge of said cushion, substantially as described. 130
